UNITED STATES PATENT OFFICE.

NINA MAE MAHAFFY, OF ARMADA, MICHIGAN.

TOOTHPHBRUSH HOLDER.

Application filed November 16, 1923. Serial No. 675,128.

To all whom it may concern:

Be it known that I, NINA MAE MAHAFFY, citizen of the United States, residing at Ar-
5 mada, in the county of Macomb and State of Michigan, have invented certain new and useful Improvements in Toothbrush Holders, of which the following is a specification.

This invention relates to tooth brush holders and has for its primary objects the pro-
10 vision of a device of this character wherein provision is made for holding a plurality of tooth brushes in convenient position for use, while at the same time maintaining the several brushes separate and protecting the same from dust and other foreign matter
15 for sanitary purposes.

Another object of the invention is to pro-
20 vide a tooth brush holder wherein provision is made for permitting a particular person to readily identify the particular brush sup-
ported by the holder which is intended for his particular use, and wherein means is pro-
vided for permitting ready removal or re-
placement of the brushes when desired.

25 A further object of the invention is to pro-
vide a tooth brush holder characterized as specified above, and wherein consideration is given to cheapness of manufacture, simplicity and durability of construction.

30 Other objects will appear as the nature of the invention is better understood, and the same consists in the novel form, combination, and arrangement of parts hereinafter more fully described, shown in the accom-
panying drawings, and claimed:

35 In the drawings, wherein like reference characters indicate corresponding parts throughout the several views:

Figure 1 is a front elevational view of a tooth brush holder constructed in accordance with the present invention.

Figure 2 is a vertical transverse sectional view thereof taken on the line 2—2 of Figure 1.

40 Figure 3 is a view partly in top plan and partly in horizontal section, taken substantially upon the line 3—3 of Figure 2.

Figure 4 is a fragmentary vertical sectional view, taken substantially upon the line 4—4 of Figure 2, and

45 Figure 5 is a perspective view of the hinged cover of the device.

Referring more in detail to the drawing, the present invention embodies a substantially rectangular horizontal elongated cas-
50 ing including a body 5 composed of top, bot-

tom and end walls, and having a transparent closure plate 6, suitably mounted in the front thereof, the rear of the casing body being closed by a depending hinged cover 7, the upper edge of which is moved with a longitudinal bead as at 8 for pivotal connection with the rear edge of the top wall of the body as shown in Figures 2 and 5.

The end walls of the body 5 have rigid rearwardly projecting arms or plates 9 that are connected at their inner or rear ends by means of a bracket plate 10 that extends parallel with and is spaced in relation to the back of the casing, whereby sufficient room is provided between the bracket plate 10 and the rear of the casing to permit rearward swinging of the cover 7 to open position as indicated by dotted lines in Fig. 2. The bracket plate 10 is provided with suitable openings as indicated at 11 for the reception of a suitable driven fastening by means of which the device may be effectively secured to a wall at a most desirable location.

The interior of the casing is divided into a plurality of compartments 12 by means of a plurality of parallel transverse partitions 13, and the bottom wall of the casing at each chamber is provided with a transverse slot extending forwardly from the rear of the casing as indicated at 14. The forward or inner portions of the slots 14 are narrower than the backs of the tooth brushes while sufficiently wide to admit the shanks of the tooth brush inwardly of the brush back, in order that the brushes will be supported as indicated by dotted lines in Figures 1 and 2 when the brush heads are disposed within the casing compartment. For facilitating insertion of the brushes, the slots 14 have their rear or outer end portions flared as at 15.

The hinged or swinging back wall or cover 7 of the casing is provided with a forward extension upon its lower end as at 16 adapted to move to a position beneath the bottom wall of the casing and to engage the rear sides of the brush shanks shown in Figure 2 for holding the brushes within the slots 14, the extension 16 being provided with a depending flange as at 17 by means of which the brushes are threaded against swinging movement and maintained in a vertical position within the narrow portions of the slots 14. The flange 17 also provides means whereby the user may readily swing the cover 7 rearwardly to open position when it

is desired to use any of the brushes the same holds.

From the above description, it is believed that the construction and operation as well as the advantages of the present invention will be readily understood and appreciated by those skilled in the art, it being noted that the herein-described device is of particular benefit for household use, wherein individual tooth brushes are employed by the several members of a family.

What I claim as new is:

In a sanitary tooth brush holder of the character described, a substantially rectangular horizontally elongated casing having a depending swinging cover at the back thereof and divided into a plurality of compartments by means of transverse partitions,

said casing having a bottom wall provided with a plurality of transverse slots opening 20 through the rear edge thereof for reception of a plurality of tooth brushes, one of said slots being provided at the bottom of each of said compartments, means to support said casing in spaced relation from a support, 25 said casing having a transparent front wall and a forwardly projecting flange upon the lower end of said cover adapted to underlap the bottom wall of the casing when the cover is closed and the free edge of said flange being bent downwardly to provide a stop with which the handle of the brushes are adapted to be engaged.

In testimony whereof I affix my signature.

NINA MAE MAHAFFY.
